United States Patent Office

Des. 191,334
Patented Sept. 12, 1961

191,334

SEWING MACHINE OR SIMILAR ARTICLE

Sidney J. Hamlett, Parma, Ohio, assignor to White Sewing Machine Corporation, Cleveland, Ohio, a corporation of Delaware

Filed Oct. 3, 1960, Ser. No. 62,338

Term of patent 14 years

(Cl. D70—2)

Fig. 1

Fig. 2

Fig. 3

FIG. 1 is a top plan view of the sewing machine;
FIG. 2 is a front elevational view thereof; and
FIG. 3 is a front quarter perspective view of the sewing machine.

The dominant features of the design reside in the portions shown in full lines and the particular arrangement, as shown.

I claim:

The ornamental design for a sewing machine or similar article, as shown and described.
